UNITED STATES PATENT OFFICE

104,572

DESIGN FOR A SPORT BELT

Florence N. Lewis, New York, N. Y.

Application February 20, 1937, Serial No. 67,770

Term of patent 3½ years

To all whom it may concern:

Be it known that I, Florence N. Lewis, a citizen of the United States, residing in New York, county and State of New York, have invented a new, original, and ornamental Design for a Sport Belt, of which the following is a specification, reference being had to the accompanying drawings, forming a part thereof.

In the drawings:—

Fig. 1 is a perspective view of a sport belt showing my new design.

Fig. 2 is a side view thereof with part of the belt broken away.

Fig. 3 is a perspective rear view with the belt partially broken away.

Fig. 4 is a perspective view showing the various compartments in open position, the belt being shown partially broken away.

I claim:—

The ornamental design for a sport belt as shown.

FLORENCE N. LEWIS.
